United States Patent Office

Des. 208,000
Patented June 27, 1967

208,000

LINK CHAIN FOR A BRACELET OR SIMILAR ARTICLE

Yuen Sang Poon, Hong Kong, assignor to Baldwin Bracelet
Corporation, New York, N.Y., a corporation of New
York

Filed Feb. 14, 1966, Ser. No. 1,028

Term of patent 14 years

(Cl. D45—4)

FIG. 2

FIG. 3

FIG. 4

FIG. 5

FIG. 1

FIG. 1 is a top plan view of a link chain for a bracelet showing my new design;

FIG. 2 is a top plan view of a single link of the link chain;

FIG. 3 is a side elevation view thereof;

FIG. 4 is an end elevational view thereof; and

FIG. 5 is an enlarged perspective view thereof.

I claim:

The ornamental design for a link chain for a bracelet or similar article, substantially as shown.
